UNITED STATES PATENT OFFICE.

SANFORD S. BURR, OF WINNETKA, ILLINOIS.

INTERCONVERTIBLE CRIB AND TABLE.

SPECIFICATION forming part of Letters Patent No. 252,730, dated January 24, 1882.

Application filed November 18, 1881. (No model.)

To all whom it may concern:

Be it known that I, SANFORD S. BURR, of Winnetka, in the State of Illinois, have invented a certain new and useful Improvement 5 in Interconvertible Cribs and Tables, of which the following is a specification.

My object is to provide a useful article of furniture that can be used as a crib or as a table, as desired. I am aware that such an article, broadly considered, is not new, but heretofore, so far as I am informed, the crib has usually been converted into a table by folding or turning up its ends, as exemplified, for instance, in my Patent No. 60,684, of January 1, 15 1867. In a crib of this kind, however, the legs are necessarily placed so near the center as to make the crib unsafe, while the article as a whole has been too complicated and expensive as well. These disadvantages have combined 20 to prevent the use or sale of the articles to any extent.

I find that a simple and entirely effective article which can readily be converted from a crib into a table, or vice versa, may be obtained by providing for use in connection with the crib ends a top and a shelf, which, when the crib sides are removed, can be fitted to the crib ends, so as to form a strong and durable table. Such an article is shown in detail in 30 the drawings, in which—

Figure 1 is a perspective view of the crib. Fig. 2 is a like view of the table. Figs. 3, 4, and 5 are details, hereinafter referred to.

A are the crib ends; and B are the crib sides 35 detachably fastened to the ends of the crib by the usual bed-irons, as indicated at *a b*, Fig. 3, or in any other customary way. That end A which is at the head of the crib may be provided with an ornamental head-piece, C; but that 40 piece, in case it is used, should be removably connected with the end A by dowels *c*, as indicated in Fig. 3, so that it may be taken off when the crib is to be converted into a table.

D is a table-top of any approved shape and 45 material, and E is a shelf. These parts are so formed and constructed with reference to the crib ends A that they may, when the crib sides B are detached and removed, be fitted to and united with the said ends, as indicated in Fig.

2. For this purpose the table-top D, which rests 50 on top of the ends A, may be provided on the under side with dowels *d*, which will enter holes *e* in the corner-posts of the ends A, as indicated in Fig. 4; or, in lieu thereof, the top may have on its under side cleats *f*, between 55 which the top rails of the ends can enter and fit closely, as indicated in Fig. 5; and if desired, the top can be further secured in place by cross-pins *g*, designed through the cleats or flanges *f* and intervening portion of the crib 60 end A; or other fastening devices may be employed to hold in place the top. In like manner the shelf E is supported by and attached to the crib ends at a point about midway of their height. This device E is a convenient 65 shelf, and at the same time acts in conjunction with the top D to brace and uphold the ends and to stiffen the table. It is supported on cleats *h*, with which the ends A are provided on their interior opposite faces, and to which 70 it may be fastened by dowels or screws, or it may be detachably but securely fastened to the ends A in other appropriate ways. The parts D E, which, as before said, are designed to be sold with the crib, are inexpensive, and 75 do not appreciably increase the price of the article.

In order to convert the crib into a table, all that is needed is to remove the crib sides, and of course the slats, and then to fit to the crib 80 ends A the top D and shelf E, as above described, and the reconversion of the table into a crib is accomplished with equal facility.

What I claim, and desire to secure by Letters Patent, is—

An interconvertible crib and table, comprising the crib ends A and the crib sides B and top and shelf D E, adapted to be connected to and interchangeably used with said crib ends 85 in the manner and for the purposes herein specified.

In testimony whereof I have hereunto set my hand this 16th day of September, 1881.

SANFORD S. BURR.
